(57) **CLAIM**

The ornamental design for a toothbrush handle, as shown and described.

DESCRIPTION

FIG. 1 is a front perspective view from top and left side of the toothbrush handle;

FIG. 2 is a front view of the toothbrush handle;

FIG. 3 is a back view of the toothbrush handle;

FIG. 4 is a left side view of the toothbrush handle;

FIG. 5 is a right side view of the toothbrush handle;

FIG. 6 is a top view of the toothbrush handle; and,

FIG. 7 is a bottom view of the toothbrush handle.

The broken lines are shown for the purpose of illustrating parts of the toothbrush handle that form no part of the claimed design.

1 Claim, 2 Drawing Sheets(56)
